(57) **CLAIM**

The ornamental design for a sun shield for a beverage container, as shown and described.

DESCRIPTION

FIG. 1 is a perspective view of a sun shield for a beverage container showing my new design.

FIG. 2 is a top plan view of the sun shield for a beverage container shown in FIG. 1.

FIG. 3 is a bottom view of the sun shield for a beverage container shown in FIG. 1.

FIG. 4 is a front elevation view of the sun shield for a beverage container shown in FIG. 1.

FIG. 5 is a rear elevation view of the sun shield for a beverage container shown in FIG. 1.

FIG. 6 is a side elevation view of the sun shield for a beverage container shown in FIG. 1; and,

FIG. 7 is a side elevation view, opposite the view shown in FIG. 6, of the sun shield for a beverage container shown in FIG. 1.

The broken lines of the sun shield for a beverage container are for the purpose of illustrating the environment and form no part of the claimed design.
